(57) **CLAIM**

I claim the ornamental design for a bicycle, as shown and described.

DESCRIPTION

FIG. 1 is a perspective view of a first bicycle of my new design;

FIG. 2 is a right side elevational view of the bicycle of FIG. 1;

FIG. 3 is a left side elevational view of the bicycle of FIG. 1;

FIG. 4 is a front elevational view of the bicycle of FIG. 1;

FIG. 5 is a rear elevational view of the bicycle of FIG. 1;

FIG. 6 is a top plan view of the bicycle of FIG. 1;

FIG. 7 is a bottom plan view of the bicycle of FIG. 1;

FIG. 8 is perspective view of a second bicycle of my new design;

FIG. 9 is a right side elevational view of the bicycle of FIG. 8;

FIG. 10 is a left side elevational view of the bicycle of FIG. 8;

FIG. 11 is a front elevational view of the bicycle of FIG. 8;

FIG. 12 is a rear elevational view of the bicycle of FIG. 8;

FIG. 13 is a top plan view of the bicycle of FIG. 8; and,

FIG. 14 is a bottom plan view of the bicycle of FIG. 8.

Any components in the appended drawings shown in broken lines are for illustrative purposes only and form no part of the claimed design or a specified embodiment thereof.
